PROCESS FOR MAKING INSULATING SIDING

Julius Z. Holimann, Larchmont, N. Y., assignor to The Patent and Licensing Corporation, New York, N. Y., a corporation of Massachusetts

Application July 26, 1952, Serial No. 301,084

4 Claims. (Cl. 117—5)

This invention relates to an improved process for making insulating siding and more particularly to an improved process for making narrow shake design insulating siding.

For many years there has been manufactured an insulating siding, particularly for the exteriors of buildings, which usually comprises an insulating board of wood fiber or the like which has been impregnated with molten bitumen, cooled, coated on one side with a bitumen in a plastic state, slated with a coating of granules of crushed slate or the like, embossed or rolled, cooled and packaged. One of the types of these boards is known as narrow shake design insulating siding which is about one-half the width of the usual insulating siding board. To make this on the machines customarily used, the productive capacity on the basis of the number of square feet of the product is reduced by one-half since it is not usually feasible to run two boards side by side through the various steps including embossing.

It is, therefore, an object of the present invention to provide an improved process for the manufacture of insulating siding.

It is a further object of the present invention to provide an improved process for the manufacture of narrow shake design insulating siding.

It is a present object of the present invention to provide an improved process for the tandem production of narrow shake design insulating siding.

These and other objects are attained by the present invention which provides an improved process for producing insulating siding comprising cutting a substantially rectangular groove in the center of an insulating board blank, applying the weather coating to said blank, and splitting said blank substantially in the middle of said groove. Thus, there are formed two boards which are substantially identical, except as will be hereinafter described.

The advantages of the invention will be apparent from the drawings which illustrate the preferred embodiment of the invention, but it will be understood that variations and substitutions may be made within the scope of the claims.

Fig. 1 is a cross sectional view of the insulating board blank before any processing.

Fig. 2 is a cross section on the line 2—2 of Fig. 3.

Fig. 3 is a diagrammatic sketch of the process.

Fig. 4 is a prospective view of the insulating board blank which has been saturated, coated, slated and partially scooped out.

Fig. 5 is a cross section of a finished narrow shake design insulating board.

Referring to the drawings, there is shown in Fig. 1 a cross section of the board 10 containing a central groove 11 and shiplap edges 12. The groove 11 is preferably cut in the board before any of the other processing steps. Referring to Fig. 2 there is shown a cross section of the board after it has been saturated, cooled, bitumen coated, slated and embossed. The bituminous coating 14 is slated with granules 15. It will be noted that the bituminous

2

coating and granules also fill central groove 11. There is also illustrated by a dotted line the proposed line of cut 16.

Referring to Fig. 4 there is shown a prospective view 5 of the board after the scooping out process has begun and disclosing the strip 17 of bituminous material and granules which has been scooped out of central groove 11.

The steps of the process are illustrated in Fig. 3 which shows a segment of the conveyor 19 which may be a roller conveyor or the like having mounted adjacent the upper surface thereof a scoop 20 or cleaning tool which may be a sharpened metal blade in the nature of a chisel. After the scooping operation the board encounters a knife 21 mounted centrally of the conveyor and adjusted to split the board substantially in the center of the groove 11. So as not to leave an untreated cut surface, there is preferably provided a wedge 22 to force the two sections of board apart against the side guide rollers or the like, such that a doctor roll 23 operating in a bituminous liquid can coat the cut surface. These steps are preceded by the saturating, cooling, coating, slating and embossing as illustrated. There then follows a cooling and packaging.

In Fig. 5 there is shown a cross section of a finished board with the original shiplap 12 and a new shiplap 25 formed in the cutting operation. This shiplap 25 is preferably shorter than shiplap 12 to permit installation of the boards with the shiplap 12 overlapping the outer face of the board rather than being flush with shiplap 25.

The boards preferably, but not necessarily, contain 30 shiplaps in the ends thereof and consequently the process produces lefts and rights. Lefts and rights of the same color will be produced in the ordinary manner, but if it is desired to produce lefts of one color and rights of another color, granules of different colors may be applied 35 to each side of the sheet while utilizing a divider in the middle. Any slight blending of the two colors which may take place in the middle is removed by the scooping process. In the ordinary insulating siding process, suction devices are used to recover granules which do not adhere, 40 the most usual of these devices being known as Pangborn devices. If two different colors are run, one on the left and one on the right, a divider plate may be placed between two Pangborns to permit granules of only one color to enter each Pangborn.

45 While narrow shake design insulating siding has been illustrated, it will be understood that the invention may be applied to other types of siding including insulating siding which is embossed so as to have a brick design. Alternatively, the process may be applied to making shingles of two different widths, in which case they would not 50 be split in half, but rather at some other predetermined point. Further, the blank may be made into more than two boards. Also alternatively, it is possible to reverse the steps of scooping out the groove and cutting to first 55 cutting and then scooping out the two grooves thus formed.

While the preferred process has been illustrated, another alternative is to place a bar of metal or the like in groove 11 during the coating and slating operations, so that 60 scooping out will not be necessary. Such a bar may be manually inserted in and removed from each board, or may be mounted above the conveyor.

I claim:

1. A process for producing insulating siding comprising cutting a substantially rectangular groove in the center of one face of an insulating board blank, applying bitumen 65 in a plastic state and granules to the thusly grooved side of said blank, scooping out the bitumen in a plastic state and granules from said groove, and splitting said blank substantially in the middle of said groove to form shiplaps on two pieces of insulating siding.

2. A process for producing insulating siding comprising cutting a substantially rectangular groove in the center

of one face of an insulating board blank, applying bitumen in a plastic state and granules to the thusly grooved side of said blank, scooping out the bitumen in a plastic state and granules from said groove, splitting said blank substantially in the middle of said groove to form shiplaps on two pieces of insulating siding, and applying bituminous material to the freshly cut edges thereof.

3. A process for producing insulating siding comprising cutting a substantially rectangular groove in the center of one face of an insulating board blank, impregnating the board with molten bitumen, cooling, coating the grooved side thereof with bitumen in a plastic state, coating with granules, embossing, scooping out substantially all the bitumen and granules from said groove and splitting said board substantially in the middle of said groove thus forming shiplaps on two pieces of insulating siding.

4. A process for producing insulating siding comprising cutting a substantially rectangular groove in the center of one face of an insulating board blank, impregnating the board with molten bitumen, cooling, coating the grooved side thereof with bitumen in a plastic state,

coating with granules, embossing, scooping out substantially all the bitumen and granules from said groove, splitting said board substantially in the middle of said groove thus forming shiplaps on two pieces of insulating siding, and applying bituminous material to the freshly cut edges thereof.
